UNITED STATES PATENT OFFICE.

ALBERT H. GENTLE, OF BIRMINGHAM, ALABAMA, ASSIGNOR OF ONE-HALF TO
HALSTEAD T. AYDELOTT, OF BIRMINGHAM, ALABAMA.

CASTING-MACHINE FOR METALLIC PACKING.

1,178,149.

Specification of Letters Patent.

Patented Apr. 4, 1916.

Application filed May 1, 1914. Serial No. 835,622.

To all whom it may concern:

Be it known that I, ALBERT H. GENTLE, a citizen of the United States of America, residing at Birmingham, in the county of Jefferson and State of Alabama, have invented certain new and useful Improvements in Casting-Machines for Metallic Packing, of which the following is a specification.

My invention relates to a casting machine 10 peculiarly adapted for the manufacture of metallic packing rings and particularly sectional packing rings wherein the sections are provided with offset lugs or shoulders which require to be carefully extracted from the 15 molds to avoid distorting or injuring the lug.

One object of my invention is to provide a machine particularly adapted for rapidly casting packing rings in metallic molds and 20 one feature of special advantage is the manner in which the top plate over the molds carrying the gates for the metal is made adjustable to clear the molds and trim off the runners.

25 Another feature of particular advantage is the manner in which the molds are journaled in the machine frame and adapted to be tilted so that the finished packing rings when ejected from their molds will fall by 30 gravity into a receiving hopper or chute and not require handling.

A further feature of novelty in my device is the manner in which the molds are constructed and arranged with reference to the making 35 of packing ring sections having an offset lug or projection, my object being to so arrange the ejecting mechanism that the lugs will not be in any manner injured or distorted when the packing rings are ejected 40 from the mold.

My invention further comprises various novel details of construction and arrangements of parts which, in their preferred embodiment only, are illustrated in the accompanying drawings which form a part of 45 this specification, and in which:

Figure 1 is a plan view of my machine with the molds in casting position and the cover plate shown shifted from over the 50 molds. Fig. 2 is a side elevation of Fig. 1. Fig. 3 is a vertical sectional elevation taken on the line $z-z$ of Fig. 1, and illustrating the molds in tilted position ready for the ejecting operation. Fig. 4 is a detail elevation 55 of the molds taken on the line $y-y$ of Fig.

3. Fig. 5 is a detail view of a part of the ejecting mechanism. Fig. 6 is a detail side elevation of the mold box as seen in Fig. 3, with the outer casing partly broken away and the ends of the molds shown in half 60 vertical section with their parts in ejecting position. Fig. 7 is a detail view of the head of the ejector cylinder.

Similar reference numerals refer to similar parts throughout the drawings.

As illustrated, my machine comprises a base 1 and side members 2 which are longitudinally grooved at 3 along their upper edges to form slideways in which are received tongues on the side edges of the 70 sliding top plate 4. This plate is provided centrally with a rack 5 that meshes with a large pinion 6 mounted on shaft 7 and driven by a small pinion 8 fast on a shaft 9 and which may be turned by a hand wheel 10. These shafts have their bearings in a 75 vertical extension 11 of the walls 2. The top plate 4 is stopped in its extreme position to the left by engaging a seat in the rear wall 12 of the frame.

I prefer to use a multiple mold frame 13 which is journaled on a bearing pin 14 and a short shaft 15, which latter is keyed fast to the frame 13 and provided with an arm 16 by means of which the frame can be 80 rocked on its bearings. Steps 16^a and 16^b are engaged by arm 16 and serve to limit the rocking of the mold in either direction, the latter being attached eccentrically to the frame to permit of a limited adjustment. I 90 have shown molds designed for the manufacture of two complete sets of packing rings, each set comprising a plain sectional ring which interfits at break joints within a sectional ring having internal lugs. As the 95 pairs of molds are duplicates, only one pair will be described. The mold chamber or chambers in the multiple mold used for casting the plain rings, has a sliding barrel 17 fitted therein and provided with an offset shoulder 18 which surrounds its outer end and engages, when in position for casting, a seat 19 (Fig. 6) in the mold chamber. The 100 barrel end is turned smooth except for opposite square raised lugs 20 and fits closely about a fixed circular head 21 which stands flush with the top of the mold box and with the top of lugs 20, when in retracted position, these lugs serving to divide the mold into half sections, as seen in Fig. 1. In its 105

110

ejecting or outer position, as seen in Fig. 6, the barrel 17 is movable so as to project beyond the top face of the mold plate. The head 21 is reduced at its outer end 22 which 5 stands flush with the top of the mold, and the head is held stationary by means of a taper pin 23 which is driven through alining openings on opposite sides of the mold chamber. The barrel 17 is provided with elongated slots 24 through which the pin passes serving both to limit the forward travel of the barrel and prevent its rotation about its longitudinal axis. To facilitate the removal 10 of the pin, its outer end is threaded and has a nut 25 thereon adapted to be screwed down to engage the mold and force out the pin. The inner end of the barrel 17 is closed by a screw plug 26 having on its inner face a stud 27 which engages one end of a coiled 15 spring 28, the other end of which engages a corresponding stud 27^a on the rear face of the head 21. This spring acts to return the barrel to its retracted or inner position.

The mold for forming the packing rings 25 which carry the internal lugs, comprises a movable barrel 29 which has slots 24 therein and is held against rotation by a pin 23^a in the same manner as barrel 17. This mold chamber has a seat 30 which an offset shoulder on the barrel engages. Within this 30 barrel is a stationary head 31 which forms the inner wall of the mold cavity and is held against movement by the pin 23^a. This head has a reduced cylindrical head portion 31^a, the outer end of which stands flush with the top face of the mold and is transversely and diagonally slotted to receive an auxiliary sliding ejector member 32. This member is made fast at its center to a pin 33 35 which passes slidably through alining openings in head 31, pin 23^a and screw plug 26, which closes the rear end of the barrel. It is provided with an offset shoulder 34 between which and the head 31 is disposed a 40 spring 35. The middle portion of the auxiliary ejector 32 fits in the slot across head 31^a, being shaped so that when retracted (see Fig. 3) it entirely fills out the slot in said head. At its inner ends however the 45 member 32 carries extensions 32^a which fit into alining slots 29^b provided to receive them in the head 29^a of barrel 29 and in a raised pattern 36 thereon. The pattern slots permit the extensions 32^a to pass down 50 through them and seat in the slots in the barrel end which they fill out. The pattern's outer peripheral edge is spaced from the wall of the mold chamber. The barrel 29 also carries pattern lugs 37 which are 55 oppositely disposed and extend flush with the top of the mold to divide the mold for casting the rings in two sections.

To the bottom of the mold box I attach a 60 pair of guide pins 38 upon which is slidably mounted a cross plate 39 stop pins 40

being driven through their outer ends to hold the cross plate 39 against disengagement from the pins. This plate 39 overlaps the rear ends of all four barrels in the mold box. I mount on the back of plate 39 a pair 70 of pins 41 which serve as guides for a diagonal plate 42 that is spaced from the plate 39 and has its outer ends adapted to engage the pins 33.

The mechanism for ejecting the casting 75 from the molds comprises preferably two separate means, one controlled by the foot lever 43 and the other by the hand lever 44. The foot lever is pivoted to a bearing plate 45 and connected by a link 46 with a bell 80 crank lever 47 keyed to a shaft 50 which is journaled in the sides 2 of the frame and projects beyond the other side where it is connected to a similar bell crank 47. These two bell cranks have slots 48 in which engage pins 49 at opposite ends of a slide frame 51 (see Fig. 5) which at its center carries a pair of spaced pins 52 arranged as they are advanced to straddle the plate 42, the mold being in the position shown in Fig. 90 3, and to strike only the plate 39. The hand lever 44 is fast on a shaft 53 journaled in hangers under the frame and provided at its center with a crank arm 54 which is connected to a link 55 that passes upwardly 95 through the frame and connects with a bell crank lever 56 journaled to turn freely on the shaft 50 and having its upper end disposed between the pins 52 and in position to engage only the plate 42.

The top plate 4 is provided with a plurality of gates 57 so arranged that when shifted above the molds each gate will admit metal to one side of each mold cavity in the multiple mold. In order to rapidly clear these gates of metal after having made a cast, I provide an ejector plate 58 disposed beneath the plate 4 when the latter stands in the position shown in Fig. 3. This plate is 105 pivotally connected to a link 59 and this link is adapted to be operated by the crank 60 on a shaft 61 which is controlled and operated by a hand lever 62. The frame walls 2 are cut away at each side and carry depending guide pins 63 which slide with a snug fit in openings provided for them in ears at each side of plate 58, which ears, see Fig. 2, work in the openings in the frame sides. Coiled springs 64 surround the pins 63 and serve to return the latter to its lowered position against the heads of said pins 63. The plate carries pins 65 which are so arranged that they will project into and clear each of the gates 57 as the plate is raised by lever 62. Springs 66 and 67, respectively, engage and support in initial position the levers 43 and 44.

In operation, assuming the molds to be in the position shown in Fig. 1, the hand wheel 10 is grasped and turned to shift top plate 4 130

to the right into position with its gates 57 in register with the several molds, whereupon the molten metal is poured into the several molds in the usual manner, it being noted that the barrels 17 and 29 and the plate 32 are retracted by their respective springs to their inner positions as shown in Fig. 3. The hand wheel 10 is now reversely turned and as the top plate is shifted to the left it 10 shears the metal runners and leaves the top faces of the packing rings smooth and clean. The lever 16 is then grasped and pulled down against stop 16^b and the mold box is rocked thereby to horizontal position which 15 brings its plates 39 and 42 into position opposite the actuators 52 and 56. Whereupon the operator depresses lever 43 and through the connection shown, shifts the pins 52 into engagement with the plate 39 and moves it 20 to force outwardly all of the barrels of all the molds, see Fig. 6, and bring their outer ends forming the bottom of the several mold cavities to a position flush with the outer face of the heads 22 and 31^a, which serves to 25 eject the plain washers cast over the barrel ends 18, but it leaves the other packing ring sections having internal lugs still held in their molds by the engagement of their lugs in the slots in the pattern 36. The ends 32^a 30 of the ejector 32 form movable bottoms for the said lug forming slots in the pattern 36, and in order to eject these ring sections without defacing the lugs, the operator next presses on the hand lever 44 and rocks the bell crank 56 into engagement with the plate 35 42, which forces the rods 33 inwardly and carries with them the plates 32, moving their ends 32^a out flush with the top walls of the pattern 36 and forcing the lugs out of the 40 pattern slots, whereupon the packing rings are ejected without injury and fall by gravity from the molds. No manual handling of the molds or of the finished casting is required by my apparatus and it operates 45 quickly and accurately to form the type of castings referred to or is available for casting other devices of like character.

Without limiting myself to the details of construction which are disclosed only in their preferred embodiment, what I claim as new and desire to secure by Letters Patent, is:—

1. In a casting machine, the combination of a frame, a multiple mold mounted therein, a top mold plate having gates therein adapted to register with the molds, means to shift said top plate laterally of the multiple mold to shear the runners and expose the finished cast articles, and ejecting means to force the finished articles from the molds, substantially as described.

2. In a casting machine of the character described, a frame, a multiple mold pivotally connected to the frame, a top mold plate 65 which is provided with gates for the molds,

means to shift said top plate to shear off the runners and finish the molded articles and also to clear the multiple mold, means to tilt the mold after its top plate has been shifted, and mechanism to eject the finished articles from the multiple mold in its tilted position.

3. In a casting machine of the character described, a multiple mold, each mold having means adapted to eject the molded article, a frame in which the multiple mold is pivotally mounted, and lever controlled mechanism adapted to actuate the ejecting mechanism when the molds are tilted from their pouring position to permit the cast articles, when ejected, to fall by gravity from the molds, substantially as described.

4. In a casting machine of the character described, a multiple mold comprising mold cavities formed between inner and outer spaced members, a reciprocating barrel forming the bottom of each mold cavity, means to hold said members in fixed relationship, means to actuate the barrels to eject the cast articles, the inner member and barrel of one or more molds being slotted to receive an independently movable ejecting member, means to move a barrel and its co-acting ejecting member simultaneously, and independently controllable means to actuate said independent ejecting member, substantially as described.

5. In a casting machine, the combination of a mold having a circular chamber therein, a circular head held in fixed central relationship in said chamber with its outer end flush with the top of the mold, a barrel movable axially of said chamber and forming the bottom of the mold cavity, a raised pattern on its outer end, the barrel head and pattern having alining recesses adapted to receive an ejecting member which is adapted to fill the slot in the end of the head and barrel but leaves open the slot in the pattern, means to move said barrel axially to move the pattern and casting beyond the chamber, and independent mechanism to move said ejector member to dislodge the casting from the pattern, substantially as described.

6. In a casting machine of the character described, a mold having a circular chamber therein, transverse alining holes in said mold, a barrel which fits slidably in the mold chamber, a head which makes a close fit in the outer end of said barrel which has oppositely disposed elongated slots, said head having an opening therethrough, a pin inserted in the alining openings in the mold and head and passing through the slots in the barrel, and mechanism to actuate the barrel to eject the molded article.

7. In a multiple mold, one or more pairs of annular mold chambers therein, movable barrels forming the bottoms of said molds,

alining openings in the inner and outer walls of each mold, a pin driven through said openings to hold the mold walls in fixed relationship, means to move said barrels outwardly free of interference with said pins comprising lever controlled reciprocatory means adapted to engage and move outwardly simultaneously the several barrels, auxiliary ejectors movable with the barrels, 10 and means to actuate said auxiliary ejectors after the barrels reach the limit of their outward travel, substantially as described.

8. In a casting machine, the combination of a multiple mold, part of said molds having a simple ejecting mechanism and the other part a compound ejecting mechanism, a common means for actuating said simple mechanisms and part of the compound ejecting mechanisms simultaneously, and independent means for simultaneously actuating the other part of the compound ejecting mechanisms.

9. In a casting machine, the combination of a plurality of molds, a top plate for molds having a plurality of gates for pouring said mold cavities, means to shift said top plate laterally from over said molds to shear the metal runners and uncover the molds, means to stop and hold said top plate in predetermined position, and a common means for simultaneously ejecting the metal runners from said gates in the top plate, substantially as described.

10. In a machine for casting packing rings, the combination of a mold chamber, a barrel fitted in the end of said chamber and axially adjustable therein, a fixed head which said barrel surrounds and which with the mold chamber forms a circular mold cavity, patterns carried on said barrel end comprising diametrically opposite flanges which divide the mold cavity into halves and raised patterns which give the cavity an angular shape in cross section, 45 alining recesses in the patterns, head and barrel end, an auxiliary ejector which in retracted position fills the slots in the head and barrel end and forms a movable bottom for the slots in the pattern, and means to independently actuate the barrel and auxiliary ejector, substantially as described.

11. In a casting machine, the combination with a multiple mold, of a sliding top plate for the mold having a plurality of gates therein, guide means to stop said plate

in predetermined position, an ejector plate disposed below said top plate when in said predetermined position, guide means for said ejector plate, ejector pins on said plate arranged to enter said gates in said top plate, and means to move the ejector plate to force its pins into said gates to clear them, substantially as described.

12. In a casting machine, a frame, a mold box pivoted to the frame, means for tilting said box, stops on the frame to arrest the box in horizontal or inclined position, ejecting devices carried by said mold box, and actuating mechanism carried by the frame and adapted to engage said ejecting devices when the mold box stands in its tilted position, substantially as described.

13. In a multiple mold, a plurality of annular molds formed by spaced members forming the inner and outer walls of annular mold chambers, means to hold said members in fixed relationship, movable barrels forming the bottoms of said mold chambers, patterns on said barrels which traverse the mold chamber radially to subdivide it into sections and which in pouring position stand flush with the top of the mold chamber, and means to move the barrels to eject the sectional casting, substantially as described.

14. In a casting machine, a frame having horizontal guides, a gated top mold plate which slidably engages said guides, a mold disposed so that said top plate fits snugly thereover while mounted on said guides, a rack on said plate, a pinion mounted on said frame and meshing with said rack, and a hand wheel for driving said pinion.

15. In combination, a mold frame, a mold box mounted thereon, molds in said box comprising each an ejecting barrel, part of said molds having an auxiliary ejector disposed above the barrel and projecting downwardly therethrough, a member movable to actuate all said barrels, a member movable to actuate said auxiliary ejectors, and independently controllable means to actuate said members, substantially as described.

In testimony whereof I affix my signature in presence of two witnesses.

ALBERT H. GENTLE.
